UNITED STATES PATENT OFFICE.

ALBERT H. STEBBINS, OF LOS ANGELES, CALIFORNIA.

PNEUMATIC SIZER.

Application filed April 8, 1922. Serial No. 550,872.

To all whom it may concern:

Be it known that I, ALBERT H. STEBBINS, a citizen of the United States, residing at Los Angeles, in the county of Los Angeles 5 and State of California, have invented an Improvement in Pneumatic Sizers, of which the following description, in connection with the accompanying drawings, is a specification, like characters on the drawings representing like parts.

The present invention relates to pneumatic sizers or separators for separating materials in accordance with their size and specific gravity.

15 Heretofore the sizing of materials has been commonly accomplished by the use of screens or screen clothing, upon which the materials are delivered so that the finer materials pass through the apertures of the 20 screening surface out of contact with the coarse materials.

In various fields of industry, and more particularly in the treatment of ores, it may be desirable to separate the materials in accordance with their sizes, and also to produce a partial classification of the materials in accordance with their differences in specific gravity to facilitate separation of the values from the foreign materials. This 30 cannot be done by the ordinary screen, because screens separate in accordance with size alone.

The present invention therefore contemplates a pneumatic sizer or separator constructed to effect the passage of air through the materials to be treated as these materials travel along a supporting surface. In sizers of this type it is important that the air currents passed through the supporting 40 surface and the materials traveling over the surface be of substantially uniform strength throughout any one portion of the supporting surface. In other words, it is important to prevent excessively strong currents from 45 passing through some apertures of the supporting surface while currents that are too weak pass through adjacent apertures, since such a variation in the currents would not properly separate the materials.

50 One important feature of the present invention therefore, consists in means disposed in spaced relation to the apertures of the supporting surface and adapted to equalize the strength of the currents passing 55 through the apertures and the materials passing over the surface.

In the sizing or separation of materials by passing air therethrough, it may be desirable to separate the lighter materials into a plurality of different grades.

Another important feature of the invention therefore consists in a supporting surface of substantial length over which the materials are passed, and of a plurality of collecting chambers arranged adjacent the 60 surface, so that different chambers receive the lighter materials removed during different stages in the passage of the materials over the supporting surface. The present invention also contemplates means for relatively varying the strength of air currents entering the different collecting chambers, and it further contemplates the use of baffle plates to promote the collecting of materials within the collecting chambers.

Other features of the invention and novel combination of parts will be hereinafter described in addition to the above, and in connection with the accompanying drawings which show one good, practical form of the 65 invention wherein:

Fig. 1 is a vertical sectional view through a pneumatic sizer constructed in accordance with the present invention, the section being taken on line 1—1 of Fig. 2.

Fig. 2 is a top plan view of the sizer of Fig. 1.

Fig. 3 is a sectional view taken on the line 3—3 of Fig. 1.

Fig. 4 is an enlarged perspective view of 90 the sizer cut by a vertical section.

Fig. 5 is an end view of Fig. 1 viewed from the left, and:

Fig. 6 is a perspective view of an apertured supporting surface to be described.

Pneumatic sizers or separators embodying the features of the present invention may be variously constructed, and in the embodiment of the invention shown, a casting is provided having a series of collecting chambers 10, to one side of which is provided a separating chamber 11, and to the opposite side is provided a regulating chamber 12. However, this is not an essential arrangement of the chambers, and in some cases it may be desirable to omit the regulating chamber 12, while in other cases it may be desirable to omit the collecting chambers 10 or both chambers 10 and 12.

In the present embodiment of the invention the material supporting surface 13 is inclined so that gravity will assist in passing

the materials over this surface. The entire casing is therefore supported in an inclined position as shown in Fig. 1 and the right hand end of the casing is supported by uprights 14 while the left hand end of the casing is supported by uprights 15.

The inclined surface 13 is relatively narrow as compared with its length and is provided with apertures to permit the passage of air therethrough, and the surface 13 fits within the bottom portion of the separating chamber 11 or is secured thereto. Materials to be separated are delivered to the upper end of the inclined surface 13 by a hopper 16 provided with an adjustable gate 17 to control the delivery of materials to the surface, and as the materials pass downwardly along the upper face of the apertured surface they are subjected to air currents passing up through the surface. In the present instance the air is drawn upwardly through the perforated surface by reducing the air pressure in the upper part of the separating chamber, but this is not an essential feature of the present invention in all of its aspects and in some cases it may be desirable to force air upwardly through the perforations.

It may be desirable to separate the lighter material picked up by the air in the separating chamber into several grades, and to this end a series of collecting chambers 10 are provided disposed along the separating chamber 11 and communicating therewith. The collecting chambers 10 preferably do not communicate and are divided one from the other by the vertical walls 18, and these chambers are so arranged that materials picked up by the air currents near the upper end of the inclined surface 13 will be carried into the first collecting chamber 10 while materials picked up further along the inclined surface 13 will be carried into other chambers 10.

In the construction shown the regulating chamber 12 is connected with an exhaust fan 19 by a conduit 20, and each of the collecting chambers 10 is connected at its upper end to the chamber 12 by the short conduits 21 having gates 22 that may be adjusted to control the passage of air from chambers 10 to the chamber 12 and thereby control the strength of the air currents carrying materials into any one of the chambers 10.

As stated, one important feature of the present invention resides in means for equalizing the strength of air passing through adjacent apertures of the surface 13, and to this end, a series of averaging partitions 23 are provided within the separating chambers 11 and extending transversely thereof between the side walls 24 and 25 of the separating chamber. These partitions extend downwardly from the top

26 of the separating chamber to within a short distance from the surface 13 and form conduits terminating a short distance from the apertures of the surface. The upper portion of the separating chamber 11 may have apertures 27 communicating with the upper portion of the collecting chambers 10, and as a result each of these conduits formed by the partitions 23 sucks air through a group of apertures in the supporting surface. Furthermore the partitions 23 prevent air currents from traveling in an inclined direction within the separating chamber.

In the construction shown the air passes from the separating chamber 11 into the collecting chambers through the apertures 27 in the side wall 25, and it is desirable to prevent the air from passing directly across the collecting chamber 11 to the conduits 21. This is accomplished by providing baffle plates 28 and 29 within the chambers 10 to deflect the air currents as indicated by the arrows in Figs. 3 and 4 thereby to promote the collecting of materials within the collecting chambers. The plate 29 is preferably provided with apertures 30 near its upper end to facilitate the passage of air. The coarser materials that travel the entire length of the apertured surface 13 without being carried from the separating chamber by the air currents, are discharged from the lower end of the surface 13 into a hopper 31, and the lighter materials that settle in the collecting chambers 10 may be discharged through the hoppers 32 at the lower end of these chambers. Some of the lighter materials will be carried over into the regulating chamber 12 and will settle therein. This chamber is therefore provided with a steeply inclined bottom wall 33 along which the materials will slide into the discharge hopper 34 at the lower end of the wall 33.

The present construction is well adapted to separate fine material into a number of different grades, and it will be apparent that by adjusting the gates 22 to subject the materials in the chamber 11 to air currents that increase in strength as the materials progress along the surface 13, each of the chambers 10 will collect therein a different grade of material.

The inclined apertured surface 13 may be variously constructed, but its construction should be such that the materials, as far as practical, are prevented from passing through the apertures of the surface. One desirable construction of a supporting surface is shown in Fig. 6 and consists of sheet metal having apertures therein through which the air enters, and lips 35 are provided extending outwardly adjacent the apertures to deflect materials therefrom. It is not essential, however, in all construc-

tions that the apertures face away from the direction in which the materials travel.

From the foregoing description when read in connection with the drawings it will be apparent that a sizer constructed in accordance with the present invention will remove the dust and lighter materials from the course materials, and that the different collecting chambers 10 will classify the lighter materials into a number of different grades. It will also be apparent that the separation of materials will be in accordance with their differences in size and specific gravity.

What is claimed is:

1. A pneumatic sizer comprising in combination, an apertured surface arranged to have materials passed thereover, a casing having a separating chamber extending upwardly from the surface, means for delivering materials to be separated to the surface, means for producing air currents passing upwardly through the apertures of the surface into the chamber, averaging partitions arranged within said chamber transversely of the surface and extending downwardly toward the surface to direct the air entering the apertures upwardly between the adjacent partitions, and collecting chamber communication with the separating chamber.

2. A pneumatic sizer comprising in combination, an apertured surface arranged to have materials passed thereover, a casing having a separating chamber extending upwardly from the surface and longitudinally thereof, means for delivering materials to be separated to the surface, means for exhausting the air in the upper portion of the chamber throughout its length to produce air currents entering through the apertures of the surface, and averaging partitions arranged transversely within the chamber and extending downwardly toward the surface to direct the air entering the apertures upwardly between correspondingly disposed walls.

3. A pneumatic sizer comprising in combination, an inclined apertured surface, a casing having a chamber above said surface, means for delivering materials to be separated to the surface, averaging partitions arranged in close proximity to each other transversely of the chamber and forming a multiplicity of suction conduits each of which terminates a short distance from a group of apertures in the surface, and means for exhausting air from the upper parts of said conduits to draw air through said apertures and the materials passing over the inclined surface.

4. A pneumatic sizer comprising in combination, an inclined apertured surface, a casing forming a separating chamber extending lengthwise of the surface, a series of collecting chambers arranged lengthwise

of said surface and communicating with the separating chamber, means for delivering materials to the inclined surface, a regulating chamber communicating with the collecting chamber, and means for exhausting air from the regulating chamber thereby to produce air currents entering the apertures of said surface and passing through the separating chamber and collecting chambers, and means for discharging the collected materials from the collecting chambers.

5. A pneumatic sizer for grading materials, comprising in combination an apertured surface arranged to have materials passed thereover, a casing forming a separating chamber over said surface, a series of collecting chambers arranged along said surface and communicating with the upper part of the separating chamber, means for producing air currents passing upwardly through the apertures of the surface into the separating chamber and from the latter into the collecting chambers, and averaging partitions within the separating chamber and extending downwardly toward said surface to prevent the air currents from traveling laterally within the separating chamber.

6. A sizer for sizing or separating materials of like specific gravity in accordance with the size thereof and for sizing or grading materials of unlike specific gravity in accordance with their relative specific gravities, comprising an inclined apertured surface to which materials are fed to pass along the upper face of the surface, means for producing air currents passing upwardly through said apertures and through the materials upon the apertured surface, and lips or projecting portions extending over said apertures and in a direction to prevent the materials passing over the surface from entering the apertures so that the heavier particles not picked up by the air will be subjected to the action of rising air currents throughout their travel along the surface and will be prevented by the lips from lodging in the apertures.

7. A pneumatic sizer comprising, in combination, an inclined apertured surface, a casing forming a chamber extending over the surface, means for feeding materials to the surface to travel along its upper face, means for producing air currents passing upwardly through the apertures of the surface and the materials thereupon, and a lip extending over each of said apertures in a direction to prevent materials passing over the surface from entering the apertures so that the heavier particles not picked up by the air will be subjected to the action of rising air currents throughout their travel along the surface and will be prevented by the lips from lodging in the apertures.

8. A pneumatic sizer comprising in com-

1
bination, an apertured surface, a casing for said surface having a chamber above the surface, means for delivering materials to be separated to the surface, averaging partitions above the surface extending transversely of said chamber in an upright position and forming a multiplicity of suction conduits each of which terminates a short distance from a group of apertures in the surface, and means for exhausting air from the upper part of said conduits to draw air through the apertured surface and the materials thereupon.

9. A pneumatic sizer comprising in combination, an inclined apertured surface, a casing for said surface having a chamber above the surface and having a multiplicity of collecting chambers arranged along the inclined surface and communicating with the upper portion of said chamber, means for delivering materials to be separated to the inclined surface, exhaust means connected with the collecting chambers and operable to create air currents passing through the apertures of the inclined surface upwardly through the separating chambers into the collecting chambers, and spaced upright partitions extending transversely of the chamber above the apertured surface to prevent the air from traveling lengthwise of said chamber.

10. A pneumatic sizer comprising in combination, a long narrow casing supported at a longitudinal inclination and constructed to form a long narrow separating chamber and a multiplicity of collecting chambers arranged along the separating chamber and communicating therewith, an apertured surface secured to and extending lengthwise

of the separating chamber, means for delivering materials to be treated to said surface to travel lengthwise thereof, a receptacle forming a regulating chamber extending along and communicating with the collecting chambers, means for exhausting air from the regulating chamber to draw air from the separating chamber into the collecting chambers and from the latter into the regulating chamber, and baffle plates in the collecting chambers to promote settling therein.

11. A pneumatic sizer comprising in combination, a long narrow casing supported at a longitudinal inclination and constructed to form a long narrow separating chamber and a multiplicity of collecting chambers arranged along the separating chamber and communicating therewith, an apertured surface secured to and extending lengthwise of the separating chamber, means for delivering materials to be treated to said surface to travel lengthwise thereof, a receptacle forming a regulating chamber extending along and communicating with the collecting chambers, means for exhausting air from the regulating chamber to draw air from the separating chamber into the collecting chambers and from the latter into the regulating chamber, and means for regulating the flow of air from the different collecting chambers to the regulating chamber thereby to vary the strength of the air drawn through different portions of the apertured surface into the separating chamber.

In testimony whereof, I have signed my name to this specification.

ALBERT H. STEBBINS.
